UNITED STATES PATENT OFFICE.

HUGH H. CRAIGIE, OF NEW YORK, N. Y.

IMPROVEMENT IN WATER-CLOSET VALVES.

Specification forming part of Letters Patent No. 126,270, dated April 30, 1872.

To all whom it may concern:

Be it known that I, HUGH H. CRAIGIE, of the city and State of New York, have invented and made a new and useful Improvement in Water-Closet Valves; and the following is declared to be a correct description thereof.

In Letters Patent No. 103,721, granted to me May 31, 1870, a valve of the same general description as the present is shown, and a reference is hereby expressly made to the said patent for a description of the parts that are common to both. My present invention relates to the peculiar manner of constructing the valve *i* so that there is less work in making said valve, and the risk of its becoming obstructed or inoperative when in use is materially lessened.

In the drawing, Figure 1 is a vertical section of the valve and its containing case and chamber, and Fig. 2 is an inverted plan of the valve *i* detached.

The inlet-pipe *a*, coupling *b* to the closet-pipe, valve *e*, and plug on the stem *f*, spring *k*, variable chamber *h*, piston *g*, and water-ways 2 and 3 are substantially the same as in the aforesaid patent.

I have shown a raised seat, *r*, for the leather *s* of the valve *e*.

The valve *i*, instead of being flat is conical, and the valve-seat is of a similar shape; and, instead of a groove being made in the seat, as

at 6 in the aforesaid patent, I flatten one side of the conical valve by filing the surface away, as at 16. The reason for this change in the valve and leakage-opening is the fact that a groove such as the aforesaid groove 6 may, under some circumstances, become obstructed by a floating fiber of wood or similar substance, and become packed and embedded in the said groove, and not wash out easily with the flow of water; while, in the case of the flattened portion of the cone at 16, the leakage can be regulated, to whatever extent is required, by filing the cone away more or less; and, there being no angles or edges, there is no possibility for the leakage-opening to become obstructed by retaining any foreign substance; and beside this the conical valve-surface is more easily ground than the flat surface in aforesaid patent.

I claim as my invention—

The conical valve *i*, flattened on one side to allow a leakage into the chamber *h*, in combination with the piston *g* and valve *e*, as and for the purposes set forth.

Signed by me this 6th day of September, A. D. 1870.

H. H. CRAIGIE.
